UNITED STATES PATENT OFFICE

165,375

HANDLE FOR REFRIGERATED CABINETS

Clare H. Kafer, Palmyra, Mich., assignor to
Revco, Inc., Deerfield, Mich.

Application July 31, 1951, Serial No. 16,088

Term of patent 14 years

(Cl. D67—3)

To all whom it may concern:

Be it known that I, Clare H. Kafer, a citizen of the United States, residing at Palmyra, in the county of Lenawee and State of Michigan, have invented a new, original, and ornamental Design for a Handle for Refrigerated Cabinets, of which the following is a specification, reference being made to the accompanying drawing, forming a part thereof.

In the drawing, Fig. 1 is a perspective of the handle constituting my design;

Fig. 2 is a front elevation thereof, on an enlarged scale; and

Fig. 3 is an elevation as viewed from either end.

The broken line showing of a cabinet to which the handle is attached is for illustrative purposes only.

I claim:

The ornamental design for a handle for refrigerated cabinets, as shown and described.

CLARE H. KAFER.
